UNITED STATES PATENT OFFICE.

JOHN W. HOYT, OF SPRINGFIELD, MASSACHUSETTS.

DESIGN FOR RAILWAY STATION.

Specification forming part of Design No. 6,760, dated July 8, 1873; application filed December 24, 1872.

To all whom it may concern:

Be it known that I, JOHN W. HOYT, of Springfield, in the county of Hampden and State of Massachusetts, have invented or produced a new Design for a Building for Railway Depots; and I do hereby declare that the following is a full, clear, and exact description of the same, reference being had to the accompanying drawings to which reference is made.

B represents the posts or columns, of which there are shown in Figure 1 a sufficient number to represent a section of the building

lengthwise, or one span; and in Fig. 2, an end view of the building. A represents the platform; E, the frame-work which supports the roof; and D, the roof.

What I claim as my invention, and desire to secure by Letters Patent, is—

The design for a building, substantially as herein shown and described.

JOHN W. HOYT.

Witnesses:

T. A. CURTIS,
CLARENCE E. BUCKLAND.
